COMBINATION SPOUT CAP AND FLINT HOLDER

Russel E. Bandfield and Clifford J. Kraemer,
Toledo, Ohio

Application October 16, 1953, Serial No. 27,191

Term of patent 14 years

(Cl. D58—26)

Fig. 1 is a side elevation of a combination spout cap and flint holder embodying our new design;

Fig. 2 is a top plan view thereof, taken on an enlarged scale;

Fig. 3 is a cross-sectional view thereof, taken on the line III—III of Fig. 2; and

We claim:

The ornamental design for a combination spout cap and flint holder, substantially as shown.
